By A. M. Smith atty.

UNITED STATES PATENT OFFICE

MOSES G. HUBBARD, OF PHILADELPHIA, PENNSYLVANIA.

CAR-STARTER.

SPECIFICATION forming part of Letters Patent No. 369,004, dated August 30, 1887.

Application filed December 7, 1886. Serial No. 220,928. (No model.)

To all whom it may concern:

Be it known that I, MOSES G. HUBBARD, of Philadelphia, county of Philadelphia, and State of Pennsylvania, have invented a new and useful Improvement in Car-Starters, of which the following is a full, clear, and exact description, reference being had to the accompanying drawing, making part of this specification.

My invention consists in certain improvements in my momentum brake and car-starter for which my application, Serial No. 209,678, for a patent was allowed October 13, 1886, and is adapted especially to traction or cable cars and to electric or other motor cars, and to improve the elements of the same in other respects.

My invention relates, first, to an improved construction and arrangement of the accumulator-spring to increase its capacity and constructing it in sections united by a coupling. I also connect the ends of the spring to the gearing and frame in a similar manner.

My invention further relates to an improved construction of the friction-clutch by means of which the force-accumulator spring is wound up with a force limited by the adhesion of the friction-clutch, and in combining therewith a ratchet or toothed clutch, which permits the employment of a permanent-pressure friction-clutch, constructed and used as hereinafter described.

My invention further relates to an arrangement for limiting the force which the said friction-clutch can exert upon the gearing and other parts connected therewith; and it consists of an adjustable pivoted and sliding safety-pawl adapted to stop the revolution of the friction-clutched winding wheel at any desired number of revolutions.

My invention further relates to the arrangement and adaptation of my mower and reaper drive-wheel automatic friction-clutch (more fully described in my application for a patent, Serial No. 216,408) with the starting or propelling wheel, whereby greater efficiency and durability are attained.

My invention further relates to an improved construction of the frame-joint for permitting both a longitudinal sliding movement and a slight revolving movement of each section of the frame in conforming to the varying position of the car-axles.

The general construction of my invention is similar to my first above-mentioned arrangement; but when applied to a cable car increased capacity is required to carry the car over the blanks which occur in the cable system, and when crossing another cable, or wherever horses are now required in connection with a cable.

In constructing my permanent-pressure friction-clutch I form the friction-surface *e* on or near the end of the long sleeve *d'*, to engage with the friction-surface of one side of the operating-wheel *M*. Another friction-surface, *e'*, is formed on the loose feathered collar *d*, which slides lengthwise of the sleeve *d'*, and said friction-surface *e'* engages with a corresponding friction-surface on the side of the operating-wheel *M*. On the opposite end of the sleeve *d'* a screw-thread is cut, upon which the nut *f* is screwed up against the spring *f'*, which is thus made to press against the collar *d* and force the friction-surfaces together, whereby the operating-wheel *M* is permanently clutched between the two friction-surfaces *e* and *e'*, and thus making the amount of driving power easily adjusted, and the space between the two friction-rims forms a chamber in the wheel *M*, which may be filled with oil, thus insuring great durability of the friction-surfaces.

On the periphery of the wheel *M* a screw or worm thread is formed, in which the free ends of the pivoted or sliding pawl *B* are guided until the wheel rotates sufficiently to bring the stop *K* in contact with the pawl *B*, which will cause the friction-clutch to slip and permit the wheel to stop, thus effectually limiting the number of revolutions of the driving-wheel *M* and the strain upon the gearing and other parts should the friction-clutch rust or oiling be neglected.

The force-accumulator *C* is more conveniently manufactured and used and is much cheaper when made in sections; but it is difficult to unite the sections, and also to attach the ends to the gears and frame substantially. To do this I bend the end of the last coil of the spring parallel with the spring and introduce this end into a hole in the flange of the coupling, as shown at *L*, and I form the hubs *b b'* on each side of the flange of the coupling, around which one or more coils of the

spring will rest and grip in a manner similar to a rope or cable around a snubbing-post, and thus greatly diminish the strain upon the end of the spring in the flange L. This flange L, 5 with its hubs b b', also serves to support the united ends of the spring on the longitudinal shaft N.

The toothed clutch A is feathered to the axle and slides thereon in such manner as to 10 engage with corresponding teeth on the end of the sleeve d', and thereby drive the winding-wheel M or be easily moved out of engagement therewith.

To diminish as much as possible the power 15 required to disengage the clutch A, I form the working-faces of its teeth on an incline sufficient to permit it to be moved out of engagement with the sleeve d' of the winding-wheel quite easily when the accumulator-spring is 20 wound or strained to its full capacity. A suitable groove, R, is formed in the hub of the clutch A to adapt it to be operated by a lever which is connected with a vertical lever or other suitable device on the front end of the 25 car, by means of which one easy movement of the driver's or engineer's hand or foot will stop or start the car.

The starting gear-wheel H may be clutched directly to the axle, as shown and described 30 in my said application, Serial No. 209,678, or it may be constructed on a loose sleeve on the axle in a manner similar to that in which my permanent-pressure friction-clutch above described is mounted on the axle, to permit its 35 being thrown out of engagement with the axle by a similar toothed clutch, as shown at T. This is convenient for backing the car without disconnecting the accumulator-spring.

The accumulator-spring may be disconnected 40 at the ratchet-coupling (shown at N²) for moving the gears to adjust the safety-pawl to wind more or less, as desired.

To construct my new frame-joint, I bore into 45 each of the sections of the side sills, O, of the intermediate frame and introduce therein an iron tube or bushing, and in this tube or bushing I insert a round iron bar of sufficient length 50 to give stability to the sills. For security and to prevent the possibility of splitting the sills 55 I bolt a piece of wide band-iron bent around the end of the sills and through which the iron bar passes. The said round iron bar is shown at O', and the pieces of band-iron bent over and bolted to the sills are shown at P.

When my invention is used on cable cars, 55 I use several accumulator-springs geared together, as shown at a a', and the ordinary automatic trips may be arranged in the track to engage and disengage the winding and propelling gearing at the proper times to carry the car over the blanks in the cable system; but for the ordinary stopping and starting of cable or other motor cars, to take on or let off passengers, the rear end of the first accumulator-spring is clutched to the frame by the toothed clutch W, so that only one spring is

used. This clutch is feathered to and made adjustable on a fixed sleeve, W', projecting from the rear bearing of shaft N, and is readily operated by the gripman to adapt it to the ordinary use, or to propelling the car over the long blanks in the cable system by the joint action of all the accumulator-springs geared together; but for other motor-cars only one spring is required, and its rear end is attached directly to the frame. Fully twenty-five per cent., and often one-half, of the propelling power required for street-cars in crowded cities is lost by the constant stopping and starting of the cars. My invention is designed to prevent this loss of power and enable the cable to start cable cars without causing the great wear and abrasion of the strands of the cable, which is the greatest source of expense in that system of propelling cars, and which renders my invention as useful for them as it is for electric motors and horse-cars.

By thus saving so large a per cent. of the aggregate power, which is entirely lost by the stopping and starting, the mechanism required 90 for propelling electric and other motor cars may be proportionately diminished in weight and cost and rendered practicable and economical, while, without my invention, the excessive weight of the mechanism required to 95 propel the cars, and also to stop and start them so frequently, would be so destructive to the road-bed and track and so expensive as to be less economical than horse-power.

Having now described my invention, I claim—

1. The spiral and circumferentially-acting accumulator-spring constructed in sections, coupled together to act as one continuous spring.

2. The combination of an accumulator-spring made in sections with a coupling for uniting said sections, substantially as and for the purpose set forth.

3. A coupling or connection provided with 110 a gripping-hub, in combination with a coil-spring, for the purposes and substantially as specified.

4. The combination of several accumulator-springs, arranged substantially as described, 115 with interposed gear-wheels connecting the same, substantially as and for the purposes set forth.

5. The combination of an operating-wheel and a permanent-pressure friction-clutch 120 whereby the operating force or strain is limited, substantially as and for the purposes described.

6. A permanent-pressure friction-clutch, in combination with a force-accumulator, for the 125 purposes and substantially as described.

7. The combination of an operating-wheel, a permanent-pressure friction-clutch, and a movable toothed clutch, substantially as and for the purposes set forth.

8. The combination of an operating-wheel with a permanent-pressure friction-clutch

adapted to be adjusted to different degrees of driving power, substantially as and for the purposes set forth.

9. The combination of a permanent-pressure friction-clutched winding-wheel with an automatic or self-acting clutched starting-wheel, substantially as and for the purposes set forth.

10. The combination of the permanent-pressure friction-clutched winding-wheel with the automatic friction-clutched starting-wheel, substantially as and for the purposes specified.

11. The combination of a movable toothed clutch, a permanent-pressure friction-clutched winding-wheel, and an automatic or self-acting clutched starting-wheel, substantially as and for the purposes described.

12. The combination of a friction-clutched winding-wheel and a toothed shifter-clutch with an automatic starting-wheel and toothed shifter-clutch, whereby the whole may be thrown out of gear, substantially as and for the purposes set forth.

13. The combination of the friction-clutched operating-wheel with a safety-stop, whereby the strain upon the gear and accumulator is limited, substantially as and for the purposes specified.

14. The combination of an adjustable stop or safety-pawl with a friction-clutched winding-wheel, for the purposes substantially as specified.

15. A force-accumulator and permanent-pressure friction-clutch, in combination with a toothed winding-clutch having the working-faces of its teeth inclined to facilitate throwing

out of gear, whereby the accumulator is easily released, substantially as and for the purposes set forth.

16. The combination of a permanent-pressure friction-clutched winding-wheel with an adjustable toothed clutch, substantially as described.

17. The combination of an automatic or self-clutching starting-wheel with a movable toothed clutch, whereby the starting-wheel may be thrown out of gear to back the car, substantially as described.

18. The combination of the ratcheted spring-connection with the safety-stop for convenient adjustment, substantially as set forth.

19. The sliding and rolling frame-joint, adapted to permit the frame to conform to the varying position of the axles, substantially as specified.

20. The combination of a permanent-pressure friction-clutched winding-wheel, a force-accumulator, and an automatic or self-acting starting-wheel, substantially as and for the purposes set forth.

21. A force-accumulator constructed in parts and adapted, one part independently of the others, for starting a car and the whole for prolonging the movement, for the purposes substantially as set forth.

In testimony whereof I have hereunto set my hand this 4th day of December, A. D. 1886.

MOSES G. HUBBARD.
